UNITED STATES PATENT OFFICE.

WILBUR M. STONE, OF NEW YORK, N. Y., ASSIGNOR OF ONE-HALF TO JAMES O'CONNOR,
OF NEW YORK, N. Y.

NOTE-SHEET-GUIDING DEVICE.

1,139,082.

Specification of Letters Patent. Patented May 11, 1915.

Application filed September 15, 1911. Serial No. 649,444.

To all whom it may concern:

Be it known that I, WILBUR M. STONE, a citizen of the United States, and a resident of New York, in the county of Kings and State of New York, have invented certain new and useful Improvements in Note-Sheet Guiding Devices, of which the following is a specification.

This invention relates to note-sheet guiding devices for automatic musical instruments.

The object of the invention is to provide means simple in construction and sensitive in operation for constantly maintaining correct registration between the perforations in a note-sheet and the corresponding apertures in the tracker-bar of an automatic musical instrument such for instance as a pneumatically actuated player-piano.

In the drawing accompanying this specification is illustrated the preferred embodiment of my improvements and Figure 1 is a front elevation thereof, parts being shown in section. Fig. 2 is a fragmentary front elevation illustrating a modification of a detail of my improvements.

The principle of this invention in whatever form it is embodied is as follows: Correct registration between the perforations in the note-sheet and the corresponding apertures in the tracker-bar, is constantly maintained by two oppositely acting means, one of said means being pneumatically worked and the other mechanically worked, each of said workings being governed by means including the covering or uncovering respectively as the case may be of a single guide opening by the note-sheet.

The usual music rolls 2 and 4 are rotatably mounted in frames 3 and 5 and roll 4 may be actuated by its shaft 40, from some source of power not shown, to feed note-sheet 6 across tracker-bar 7. Said tracker-bar is mounted for movement in the direction of its length, transverse the direction of travel of note-sheet 6 in suitable bearings in side frames 3, 5, and may be provided with the usual music apertures 8, 8. Note-sheet 6 is provided with the usual perforations 9, 9 which, as said note-sheet passes across tracker-bar 7 normally register with corresponding apertures 8, 8 in said tracker-bar 7 thereby admitting atmosphere through said apertures to the usual ducts not shown, whereby the mechanism of the musical in-

strument is set in motion to sound the notes indicated by the sheet perforations.

Preferably adjacent to one edge of the path of said note-sheet, tracker-bar 7 is provided with a single guide opening 10 communicating by pipe 11 with pneumatic means operable through suitable mechanical connections for moving said tracker-bar endwise in one direction for maintaining correct registration between the perforations in the note-sheet and the apertures in said tracker-bar. For moving said tracker-bar in the other direction I provide mechanical means such as spring 12. Said pneumatic means comprises actuating pneumatic 13 having its wall 14 fixed to support 15 of valve box 16. Movable wall 17 is hinged at 18 to fixed wall 14 and is provided with ear 20 connected with tracker-bar 7 by link 21. To movable wall 17 I also attach one end of pull spring 12 and secure the other end of said spring to some convenient fixed support as frame 3.

Vacuum chamber 23 in valve box 16 is connected by pipe 24 with some well-known source of exhaust not shown. Said vacuum chamber is connected with the atmosphere by passage 25 and said passage is connected midway its length by passage 26 and pipe 27 with actuating pneumatic 13. Double valve 28, 29 on stem 30 is efficient to alternately close passage 25 against atmosphere and against vacuum. Primary pneumatic 31, in vacuum chamber 23 operatively engages button 32 on the inner end of valve stem 30, and is pneumatically connected at 33 with pipe 11 from guide opening 10. Said primary pneumatic is provided with the usual bleed opening 34, into vacuum chamber 23.

While I prefer to arrange guide opening 10 to be covered or uncovered as the case may be directly by that portion of the note-sheet adjacent to one edge thereof as illustrated in Fig. 1, other arrangements for covering or uncovering said guide-opening are equally applicable and within the scope of my improvements. For instance in Fig. 2 I have illustrated a series of perforations 35, 35 in the note-sheet more or less remote from the edge thereof, for co-action with guide opening 10 in the tracker-bar. In this arrangement said guide opening is of sufficient length transverse said tracker-bar to bridge, one after another, as the note-sheet travels across the tracker-bar, those portions of said note-sheet between said perforations 35,

35. There is thus afforded continuous operability between said series of perforations and said guide opening 10, in every way the same as if said guide opening coacted with 5 the edge portion of the note-sheet-as in Fig. 1.

The mode of operation of my improved device is as follows: In Fig. 1 guide opening 10 is illustrated as having been just covered 10 by note-sheet 6, whereby the entrance of atmosphere to tube 11 and primary pneumatic 31 has been shut off. Said pneumatic 31 is therefore collapsed by button 32 on valve stem 30 by atmospheric pressure on valve 28 15 whereby said valve is seated to shut off atmosphere from channel 25 and valve 29 is opened to permit the action of vacuum from chamber 23 to exhaust, through channels 25 and 26 and tube 27, actuating pneumatic 13. Said pneumatic is shown in Fig. 1 as just 20 about to collapse under the pressure of atmosphere and against the tension of spring 12. As actuating pneumatic 13 collapses, its movable wall 17 is moved to the left and 25 through link 21, draws tracker-bar 7 with it thus drawing guide opening 10 from under note-sheet 6 and allowing atmosphere to rush through tube 11 into primary pneumatic 31 which thereupon expands against 30 button 32 of valve stem 30 closing valve 29 and shutting off vacuum from actuating pneumatic 13. By the same means valve 28 is simultaneously opened, admitting atmosphere to said pneumatic 13 which thereupon 35 opens under the pull of spring 12 and tracker-bar 7 and guide opening 10 are moved to the right, whereby said guide opening is restored to its position under cover of note-sheet 6. The uncovering and 40 covering of said guide opening for the admission of atmosphere therethrough and the shutting off of atmosphere therefrom respectively is then repeated indefinitely, whereby tracker-bar 7 is held in a state of 45 lengthwise unstable equilibrium, fluctuating back and forth through a short stroke relatively to edge 60 of note-sheet 6. Thus whether said note-sheet is traveling in its normal path or whether it deviates there- 50 from either to the right or left its edge 60 travels constantly directly over the outer edge, relatively to the note-sheet, of constantly shifting guide opening 10. Any de-

viation of said note-sheet from its normal path of travel over said tracker-bar is thus 55 continuously met by a substantially equal deviation in the same direction by tracker-bar 7. It will therefore be seen that correct registration between the perforations in the note-sheet and the apertures in the tracker-bar is constantly maintained, no matter what the lateral deviation of said note-sheet may be by the opposite alternate endwise movements of tracker-bar 7 governed by the alternate covering and uncovering of guide 60 opening 10.

I claim:

1. In a note-sheet guiding device the combination of a tracker-bar, a single guide opening appurtenant to said tracker-bar, an actuating pneumatic for shifting said tracker-bar in one direction, a spring for shifting said tracker-bar in the opposite direction, a single valve for governing the action of said actuating pneumatic and said spring, a primary pneumatic for actuating said valve, the action of said primary pneumatic in opposite directions being governed by means including the admission of atmosphere and the closing against the admission of atmosphere respectively, of said guide opening by the note-sheet.

2. In a note-sheet guiding device the combination of a tracker-bar mounted for movement in the direction of its length, an actuating pneumatic for shifting the tracker-bar in one direction, a spring for shifting said tracker-bar in the other direction, a single guide opening fixed relatively to said tracker-bar, and means consisting of one primary pneumatic and one valve, whereby when said guide opening is covered or uncovered as the case may be by the note sheet said actuating pneumatic is caused to move the tracker-bar, and when said guide opening is uncovered or covered respectively by said note-sheet said spring is permitted to move said tracker-bar.

Signed at New York, N. Y., this 14th day of September, 1911, before two subscribing witnesses.

WILBUR M. STONE.
